UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

BRACKET FOR ANGULAR-WALLED TUBING.

1,391,103.

Specification of Letters Patent. Patented Sept. 20, 1921.

Application filed June 10, 1920. Serial No. 338,068.

To all whom it may concern:

Be it known that I, WILLIAM B. FOSTER, a citizen of the United States, and a resident of Utica, in the county of Oneida and State of New York, have invented certain new and useful Improvements in Brackets for Angular-Walled Tubing; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to brackets for use with square or other angular-walled tubing.

In bedstead and crib construction having square or other angular-walled tubing it is found that a bracket attached to and bearing simply against the flat side of such tubing tends to distort or cave in the flat side or wall of the tubing opposite the foot of the bracket. This is so especially where the bracket is subjected to sharp shocks or blows as is the case where the bracket is used to arrest the downward movement of the sliding side of a crib.

It is the purpose of my invention to provide a bracket which will obviate the above named disadvantage and which will be simple in construction and attachment and efficient and durable in use.

A further purpose is to provide a bracket of such construction that the shock or pressure transmitted to the bracket will be transmitted not simply against the flat side of the tubing, but against the adjacent angles of the tubing which are well adapted to resist the pressure.

A further purpose is to provide in combination with such a bracket means for preventing the bracket from twisting or becoming displaced upon the tubing when the bracket is fastened by a single bolt or rivet to the tubing.

Figure 1 is an isometric projection of a bracket embodying my invention as applied to a section of square tubing.

Fig. 2 is a central vertical cross-sectional view through the bracket and tubing shown in Fig. 1.

Fig. 3 is a perpendicular sectional view on line 3-3 of Fig. 2.

Fig. 4 is a side elevation of the side of the bracket which engages the tubing with the outline of the tubing shown in dotted lines.

Referring to the drawings in a more particular description it will be seen that I have illustrated the bracket embodying my invention in connection with a section of square tubing 6 of which the side 7 is engaged by the bracket. The sides of the tubing, namely 8 and 9 adjacent the side 7 form the corners or edges 8^a and 9^a.

The bracket 10 may be varied as to its shelf portion 11 according to the purpose of the bracket. In the drawings I have illustrated a bracket having in its shelf portion 11 a longitudinally extending slot 12 to adapt the shelf to be used in a sliding side crib to support the projecting ends of a sliding side in which construction a guide rod extends downwardly through the slot 12 as a guide for the sliding side all as well known in that branch of the art so not further described herein, as it is not material to my invention.

The bracket has its tube engaging portion 13 extend downward and toward its lower end is extended laterally preferably as shown in the drawings in both directions sufficiently to form two opposite lower ends 85 or arms 14 which will bear against the opposite edges 8^a and 9^a of the tube side 7.

Preferably the bracket will have its shelf portion 11 and its tube-engaging portion 13 connected by bracing webs 15. Toward the upper portion of the tube-engaging portion 13 the bracket will be provided with means for attaching the bracket to the side 7 of the tubing. A simple form of said fastening means is to provide a hole 16 in the upper portion of the part 13 through which may be placed a bolt or rivet 17 whereby the bracket is attached to the tubing in an obvious manner.

It will now be seen that downward pressure or shocks or blows taken upon the shelf portion 11 of the bracket will be communicated to the tube 6 not simply against the middle or intermediate flat portion of the side 7 but through the extended lower end 105 or arms 14 of the bracket against the edges

8^a and 9^a of the tube which obviously are opposite the adjacent walls 8 and 9 which form angular reinforcements for the edges 8^a and 9^a directly engaged by the arms 14. 5 In this way the tube is protected from being bent or distorted even by repeated shocks or blows given the bracket.

In order to prevent the bracket from twisting or becoming displaced upon the 10 tubing when attached thereto by only one rivet 17 the bracket is preferably provided with fingers 18 projecting from the arm portions 14 past the extreme edges 8^a and 9^a of the side 7 and a short distance around, 15 onto or opposite the adjacent opposite sides 8 and 9 of the tube. It will now be seen that when a bracket is made of proper size and proportion to fit a given shaped and sized tube 6 these fingers 18 will prevent 20 the bracket from swinging upon the rivet 17 as a pivot and so aid in locating the

bracket when it is being placed upon the tubing and will prevent displacement of the bracket when once in place.

What I claim as new and desire to secure 25 by Letters Patent is:

A bracket for use against angular-walled tubing comprising an outwardly-projecting shelf-portion, a downwardly-extending tube-engaging portion adapted to bear against one flat side of the tubing, said downwardly-extending portion having its lower part extended laterally sufficiently to bear against the opposite edges of the engaged tube side whereby the adjacent angles of the tube 35 take the pressure from the bracket and fingers on said laterally extended parts extending around the said adjacent angles of the tube.

In witness whereof I have affixed my sig- 40 nature, this 2d day of June, 1920.

WILLIAM B. FOSTER.
